UNITED STATES PATENT OFFICE.

JAMES S. FREW AND EDWARD A. LEWIS, OF LANCASTER, CALIFORNIA.

SOIL GRADING AND LEVELING DEVICE.

1,257,838.

Specification of Letters Patent. Patented Feb. 26, 1918.

Application filed April 3, 1916. Serial No. 88,642.

To all whom it may concern:

Be it known that we, JAMES S. FREW and EDWARD A. LEWIS, citizens of the United States, residing at Lancaster, in the county 5 of Los Angeles and State of California, have invented new and useful Improvements in Soil Grading and Leveling Devices, of which the following is a specification.

10 My object is to make a scraper and leveler wholly pivotally mounted upon independent runners adapted to run both ways so as to increase the flexibility and ease of manipulation.

15 The invention is illustrated in the accompanying drawings in which:

Figure 1 is a perspective view taken as looking into the device from the rear and shows it as adjusted for use as a leveler.

20 Fig. 2 is a view of the device in elevation.

Fig. 3 is a view similar to Fig. 2 and shows the device in an intermediate position.

Reference being had to Figs. 1 to 3 inclusive of the drawings, 10 and 11 indicate 25 a pair of spaced shoes or runners which constitute the running gear for the device, said runners being independent of each other. Superimposed thereon is a grading cant board 12 which is mounted at its ends upon 30 pivot pins 13 secured at the lower corners of the cant board, engaging ears 14 extending upwardly from the runners, said runners being under the ends of the cant board. Rigidly secured along the lower edge of 35 said cant board between the runners is a metal leveling blade 15 here shown as secured thereon by means of bolts 16 which pass through openings within the cant board. The cutting edge of the blade 15 is 40 designed to project a short distance beyond the bearing faces of the runners when the cant board is positioned vertically, as shown in Fig. 3.

The runners 10 and 11 are preferably cast 45 iron shoes having straight central portions, slightly up-turned rear ends, and forward ends up-turned to a semi-circle. The ears 14 are formed integral with the runners substantially at their longitudinal centers and 50 extend upwardly from the outer sides of the runners, so that the cant board will strike the up-turned ends of the runners when tipped forwardly or backwardly far enough. Each runner may vibrate freely independent 55 of the other runner to the limits allowed by the up-turned ends striking the cant board.

There is a great advantage in mounting the runners independently as shown and described, especially in rough work, where one runner may be going up hill and the other 60 down hill at the same time.

The cant board is reinforced along its back by means of reinforcing straps 17 here shown as six in number and having formed upon the two central ones approximately 65 mid-way of their length, bosses 18 to form pivot bearings. An operator's platform 19 is pivotally secured to the rear of the cant board intermediate its ends and approximately mid-way between its longitudinal 70 edges; the platform having its inner end pivoted to the bosses 18 and adapted to have its outer end 20 to rest and drag upon the ground. Draw chains 21 are connected to the cant board adjacent its outer ends on a 75 plane between the pivotal connection of the cant board to the runners and the pivotal connection of the platform.

Angular adjustment is afforded the grading cant board by means of adjusting mechanism 22 which allows the operator to optionally select the relation to be maintained between the cant board and the operator's platform 19 and when the desired position is reached the cant board and the platform 80 may be locked. This mechanism consists in a toothed segment 23 mounted approximately mid-way the length of the platform 19 and in the center thereof. A pivotal mounting 24 is secured at a point approximately adjacent the center of said segment 85 and concentric with its arc. Pivoted upon a pin 25 is a cant board controlling lever 26 which extends upwardly and is provided with a pawl 27 adapted to 90 engage the teeth 28 formed upon said segment. The pawl 27 is operated by means of a hand-grip 29 pivotally secured near the grip 30 upon the lever 26. Movement of the grip 29 causes a connection rod 31 to draw 100 the pawl away from the segment and allow free movement of the lever. Connection from the lever to the cant board is had by means of a connecting rod 32 mounted at a point adjacent the pivotal bearing of the 105 lever 26 and having its opposite end pivotally mounted within a bearing plate 33 secured near the upper edge of the cant board and upon its back.

In the operation of the device, when it is 110 desired to use our combination scraper and leveler for leveling soil, the grading cant

board is positioned as shown in Fig. 2. This throws the leveling blade 15 ahead of the pivotal mounting 13 provided for the cant board and allows said blade to penetrate the soil and throw it up along the face of the grading board. It is evident that as the grading board and leveling blade are canted away from the vertical the penetration of the leveling blade will be greater, owing to 10 the lessened resistance of the grading board to the soil thrown thereon. When it is desired to use the device as a scraper, the driver operates the grip 29 upon the lever 26 releasing the pawl from the segment and allowing the lever to be forced forward. This in turn forces the cant board into a vertical position, as shown in Fig. 3. Upon 15 continued forward movement of said lever 26 the grading cant board will encounter the upturned portion 38 of the runners 10 and 11 and as the device is being drawn by draw-chains 21 secured to the grading board by 20 means of I-bolts 40 the runner will be lifted at its rear edge from the ground and the weight of the device will bear upon arcuate 25 face 41 of the runners. It will be seen that in the event the driver stands upon the operating board or that sufficient weight is placed thereon, the board 19 will remain 30 in contact with the ground at its rear end 20 and irregularities in the soil will be smoothed out as the grading cant board encounters them. This is possible due to the fact that the cant board has now assumed an 35 angular position ahead of the runner and

causes the dirt to pass beneath the leveling blade instead of forcing it ahead as was done in the leveling operation.

It will thus be seen that we have provided a combined leveler and scraping device which 40 may readily be converted from the one use to the other, which has few movable parts and is simply operated and constructed.

What we claim is:

In a soil scraping and leveling device, a 45 grading cant board, a blade extending downwardly from the lower edge of said board and longitudinally thereof, a platform pivotally mounted to the opposite side of the cant board and adjacent the upper edge 50 thereof, a lever pivotally mounted upon the platform, means whereby said lever may be locked in different positions, a connecting rod between the lever and the upper end of the cant board whereby the angle between 55 the cant board and the platform may be varied, draw chains connected to the cant board and by which it and the platform may be pulled, runners pivotally mounted under the opposite ends of the cant board for sup- 60 porting the cant board during operation, and arcuate up-turned ends formed at the front of the runners against which the cant board may be swung and by which the blade may be supported in an inoperative posi- 65 tion.

In testimony whereof we have signed our names to this specification.

JAMES S. FREW.
EDWARD A. LEWIS.
